MEANS FOR CONTROLLING THE SUPPLY
OF HOT LIQUID TO A CONTAINER

Charles James Beaver and Thomas James Fairfield, Bowdon, England, assignors to W. T. Glover and Company Limited, Manchester, England, a British company

Application May 27, 1935, Serial No. 23,780
In Great Britain June 2, 1934

7 Claims. (Cl. 207—1)

This invention deals with the automatic supply of predetermined quantities of hot liquid. It is, for instance, applicable to the supplying of molten lead to a feeding vessel of an extrusion press of the kind described in United States patent application Serial No. 655,058, filed February 3, 1933, in which a vessel is mounted on the top of the container of the press and accordingly rises with the container as extrusion takes place. By the present invention such a vessel can be given at each cycle of operation a predetermined quantity of molten lead at the appropriate stage of its movement.

In accordance with the invention, we use in combination means actuated by the relative movement of the receiving and supplying parts of the systems to cause the commencement of the supply when the parts are in appropriate relative positions, and means actuated by heat received from the hot liquid supplied influenced by temperature to cut off the supply when the predetermined quantity has been given.

When applied to apparatus in which the receiving vessel moves, the invention provides that filling can commence when the vessel passes a definite point and may stop when the delivery of the appropriate quantity has produced a predetermined effect by the influence of the heat of the liquid on a thermometer bulb or other thermal responsive device which is placed in position so as to become submerged in, or to come otherwise under the influence of, the hot liquid.

It is preferred to make use of an electrically-actuated relay for opening and closing the valve for the supply of the liquid and to use, for the control of this relay, switches actuated, in one case, by relative movements and, in the other case, by a temperature responsive device. It is also preferred to connect in these control circuits signal lamps or other devices to indicate the stage of operation which has been reached at any time.

A way in which the invention may be applied to a lead press of the kind described in United States patent application Serial No. 655,058 will now be described, by way of example only, with reference to the accompanying drawing which shows a lead press furnished with means for charging a predetermined quantity of lead, withdrawn from a melting pot, periodically into the feeding vessel mounted on top of the container of the lead press.

By referring now to the drawing it will be observed that the lead press is of the vertical type consisting of a container *a* from which molten

metal is forced by the ram *b* into the die box *c* as the container is moved vertically upwards by the hydraulic ram *e*. A feeding vessel *d* is arranged at the top of the container *a* in the manner described in the specification of application No. 655,058. This feeding vessel constitutes that one of two relatively movable vessels into which hot liquid is automatically supplied. The lead melting pot *f* constitutes the second of these two vessels. This melting pot is fixed and arranged with its delivery valve *g* above the highest level reached by the feeding vessel *d*. A hinged chute *h* leads from the valve *g* to a point above the feeding vessel in the upper parts of its travel. The valve *g* is controlled by a device *i* known as a thruster which, in this case, consists of an electric motor actuating a centrifugal pump and causing oil to flow from one side of a piston to the other so as to move the piston upwards and hold it in the raised position while the motor is running. This upward movement opens the valve *g*. The downward movement, which takes place when the circuit of the motor is opened, is assisted by a weight *j* attached to the valve lever *k* on which the thruster acts. Alternatively, or in addition, the downward movement of the valve may be assisted by spring force.

From the mains *l* to the thruster motor *m* the circuit passes through a main switch M. S. and two controlling switches, one, *n*, serving to start the motor and the other, *p*, to stop it. The starting switch is provided with two rocking arms *q*¹ and *q*² which lie in the path of a projection *s* carried by the press table on the hydraulic ram *e*. As the container *a* rises and reaches the point at which filling of the feeding vessel *d* should commence, this projection *s* engages the arm *q*¹ and lifts it, thereby closing the switch *n*. Since the stopping control switch *p* is normally in the closed position, the thruster motor *m* is started and the valve *g* is opened and molten metal flows down the chute *h* into the feeding vessel *d*.

The stopping control switch *p* is of the mercury type and is controlled by a Bourdon tube *t* connected through a capillary tube *u* with a thermometer bulb *v* located in the upper part of the feeding vessel *d*. When the molten lead reaches this bulb and covers it, the heat causes the liquid in the bulb to expand and thereby communicate pressure to the Bourdon tube which rocks the mercury switch *p* and opens the circuit, thus causing the thruster motor *m* to stop and the valve *g* of the melting pot to close. Means are provided for adjusting the angular setting of the

mercury switch *p* to give the best operating conditions.

When the feeding vessel *d* has delivered its charge of molten metal to the container *a*, which takes place when the container has been lowered to the bottom of its travel, the thermometer bulb *v* is uncovered and accordingly cools and thereby brings about the re-closing of the mercury switch *p*. In the meantime, however, the lowering of the container has caused the projection thereon to engage the second arm *q*² of the switch *n* and thereby to rock this arm and open the switch. Accordingly the thruster motor does not re-start until the container rises again and closes the starting switch *n*.

A subsidiary mercury switch, not shown, is preferably included in the circuit to produce a break in the circuit of the thruster motor *m* in the event of the thermometer bulb *v* or capillary tube *u* becoming damaged.

Three signal lamps are arranged as follows. A red lamp *x* is connected across the mains between the main switch *M. S.* and the starting switch *n* so that it is illuminated whenever the mains are alive. A blue lamp *y* is connected across the mains at a point between the starting switch *n* and the stopping switch *p* so as to show when the starting switch is closed. This indication is independent of the stopping switch. A yellow lamp *z* is connected across the mains between the stopping switch *p* and the thruster motor *m*. This will accordingly light up only when both control switches are closed and the motor circuit is alive.

35 In the normal conditions of operation, the red lamp *x* is continuously illuminated. The blue and yellow lamps are lit up simultaneously when the container *a* rises to the point at which filling of the feeding vessel *d* should commence. The yellow lamp *z* is extinguished when filling of the vessel stops. The blue lamp *y* is extinguished simultaneously with the opening of the starting switch *n* during the downward movement of the container.

45 What we claim as our invention and desire to secure by Letters Patent is:—

1. In a lead press having a rising and falling container on the top of which is mounted a feeding vessel into which molten metal is fed from a melting pot and from which the metal is discharged into the container when the container is lowered, means for automatically controlling the supply of molten metal from the melting pot to the feeding vessel, said means comprising a valve governing the flow of metal from the melting pot to the feeding vessel, means comprising an electric relay for opening said valve, means for closing said valve, a circuit extending from a source of supply to the said relay, a starting switch and a stopping switch inserted in said circuit, means, associated with the container, for closing the said starting switch when the feeding vessel is raised to the point at which filling is required to commence and for opening it before

65 the re-closure of the stopping switch owing to the discharge of the metal from the feeding vessel into the container takes place, and means comprising a thermometer located in the upper part of the feeding vessel, for opening the stopping switch when the molten metal in the feeding vessel has attained a predetermined level.

2. Means for effecting the automatic supply of predetermined quantities of hot liquid to one of two relatively movable vessels from the other, comprising a valve for arresting the flow of

liquid, means controlled by the relative movement of the two vessels for opening said valve when the parts are in appropriate relative positions, and means actuated by heat received from the hot liquid supplied for closing said valve when the predetermined quantity has been supplied.

3. Means for effecting the automatic supply of predetermined quantities of hot liquid to one of two relatively movable vessels from the other, comprising a valve for arresting the flow of the liquid, an electrically actuated relay operating upon the said valve to control the flow of liquid therethrough, a circuit extending from a source of electric supply to said relay, means comprising a switch included in said circuit and actuated by movement of one vessel relative to the other, for causing said valve to open when the two vessels are in appropriate relative positions and means, comprising a second switch included in said circuit and actuated by heat received from the hot liquid supplied, for causing said valve to close when a predetermined quantity of liquid has been supplied.

4. Means for effecting the automatic supply of predetermined quantities of hot liquid to one of two relatively movable vessels from the other, comprising a valve for controlling the supply of the liquid, an electrically actuated relay operating upon the said valve to control the flow of liquid therethrough, a circuit extending from a source of electric supply to said relay, means comprising a switch included in said circuit and actuated by movement of one vessel relative to the other, for causing said valve to open when the two vessels are in appropriate relative positions, and means for causing said valve to close when a predetermined quantity of liquid has been supplied, said closing means comprising a thermometer bulb placed in the receiver vessel and actuated by heat received from the hot liquid supplied thereto, a Bourdon pressure tube placed in communication by a capillary tube with said bulb, and a second switch included in the said circuit and actuated by movement of the said pressure tube.

5. In an extrusion press having a rising and falling container on which is mounted a feeding vessel into which molten metal is fed from a storage vessel and from which the metal is discharged into the container when the container is lowered, means for automatically controlling the supply of molten metal from the storage vessel to the feeding vessel, said means comprising a valve governing the flow of metal from the storage vessel to the feeding vessel, means actuated by movement of the container for opening said valve when the feeding vessel is raised to the point at which filling is required to commence and means, actuated by heat received from the molten metal supplied to the feeding vessel, for closing said valve when the predetermined quantity has been supplied.

6. In an extrusion press having a rising and falling container on which is mounted a feeding vessel into which molten metal is fed from a storage vessel and from which the metal is discharged into the container when the container is lowered, means for automatically controlling the supply of molten metal from the storage vessel to the feeding vessel, said means comprising a valve governing the flow of metal from the storage vessel to the feeding vessel, an electrically actuated relay operating upon said valve to control the flow of metal therethrough, a circuit ex-

tending from a source of electric supply to said relay, means comprising a switch, included in said circuit and actuated by movement of the container, for causing said valve to open when the feeding vessel is raised to the point at which filling is required to commence, and means, comprising a second switch included in said circuit and actuated by heat received from the molten metal supplied to the feeding vessel, for causing said valve to close when a predetermined quantity of molten metal has been supplied.

7. In an extrusion press having a rising and falling container on which is mounted a feeding vessel into which molten metal is fed from a storage vessel and from which the metal is discharged into the container when the container is lowered, means for automatically controlling the supply of molten metal from the storage vessel to the feeding vessel, said means comprising a valve governing the flow of metal from the stor-

age vessel to the feeding vessel, an electrically actuated relay operating upon said valve to control the flow of metal therethrough, a circuit extending from a source of electric supply to said relay, means comprising a switch, included in 5 said circuit and actuated by movement of the container, for causing said valve to open when the feeding vessel is raised to the point at which filling is required to commence, and means for causing said valve to close when a predetermined 10 quantity of molten metal has been supplied, said closing means comprising a thermometer bulb placed in the receiver vessel and heated by the molten metal supplied, a Bourdon pressure tube placed in communication by a capillary tube 15 with said bulb, and a second switch included in the said circuit and actuated by movement of the said pressure tube.
